UNITED STATES PATENT OFFICE

SIEGFRIED W. GREGERSEN, OF CROOKSTON, NEBRASKA

HAMMER

Application filed April 27, 1925. Serial No. 26,135.

The object of the invention is to provide a hammer equipped with means for holding in the hand grasping the hammer, the nail to be used and effecting the initial starting of the nail as where the hammer is used by a one-handed person or when the left hand is used to hold the board or the like while starting a nail; and to provide a construction of this character in which provision is made for holding nails of different lengths so that they may be readily started in the board with the one hand holding the hammer.

With this object in view, the invention consists in a construction and combination of parts of which a preferred embodiment is illustrated in the accompanying drawings, wherein:

Figure 1 is a side elevational view of a hammer constructed in accordance with the invention.

Figure 2 is a top plan view.

Figure 3 is a longitudinal sectional view on the plane indicated by the line 3—3 of Figure 1.

Figure 4 is a transverse sectional view on the plane indicated by the line 4—4 of Figure 1.

The hammer head 1, which may be cast or drop forged or machined out of solid stock, depending on the grade of tool to be produced, is formed with lateral lugs or projections 2 and 3 in the region of the eye of the head, these lugs or projections constituting abutments for the heads of nails 4 indicated in dotted lines in Figure 1. The hammer head adjacent the abutments 2 and 3 is recessed, as indicated at 5, to provide clearance spaces for the nail heads to permit the shanks to lie against the head and against the peripheral edge of the poll 6.

Formed integral with the hammer head on the shank 7 of the poll is a lateral rib 8 extending axially of the poll and on a line intermediate between the axial line of the shanks of nails engaging the two abutments, so that a nail whose head is engaged with the abutment 2 may lie against the under side of the rib while a nail whose head is engaged by the abutment 3 may lie against the upper side of the rib. The abutment lugs 2 and 3

are arranged one closer to the poll 6 than the other to accommodate nails of different lengths to permit the point projecting beyond the poll.

In the use of the device, the initial starting of the nail is effected by placing it with the shank in engagement with the rib and the head in engagement with the desired abutment, it being retained in this position by the thumb when the head of the hammer is grasped in the hand. A single blow is then sufficient to effect the necessary penetration into a board to retain the nail in the board and following this, the handle of the hammer may be grasped in the hand and the nail driven home. The lugs 2 and 3 provide the impact elements of the initial starting and the rib a lateral abutment to maintain the alignment of the nail with the hammer head.

The invention having been described, what is claimed as new and useful is:

1. A hammer head having lateral nail abutment lugs and an adjacent rib for lateral abutment with the shank of the nail, the lugs being laterally spaced and spaced different distances from the hammer poll and the rib being arranged on a line intermediate between the axial lines of the lugs. 75

2. A hammer head having lateral nail abutment lugs and an adjacent rib for lateral abutment with the shank of the nail, the lugs being laterally spaced and spaced different distances from the hammer poll and the rib being arranged on a line intermediate between the axial lines of the lugs, and the hammer being recessed adjacent the lugs to provide clearance spaces for nail heads to permit the shanks to lie against the side of the head. 85

In testimony whereof he affixes his signature. 90

SIEGFRIED W. GREGERSEN.
